Paul E. Spahn, Perrysburg, Ohio, assignor to
Libbey-Owens-Ford Glass Company, Toledo,
Ohio

Application December 13, 1950, Serial No. 13,408

Term of patent 14 years

(Cl. D26—1)

To all whom it may concern:

Be it known that I, Paul E. Spahn, a citizen of the United States, residing at Perrysburg, in the county of Wood and State of Ohio, have invented a new, original, and ornamental Design for Soldering Iron Head or the like, of which the following is a specification, reference being had to the accompanying drawing, forming a part hereof.

Fig. 1 is a perspective view of a soldering iron head or the like, showing my new design;

Fig. 2 is a front end view of the soldering iron head;

Fig. 3 is a rear end view of the same;

Fig. 4 is a top plan view of the same; and

Fig. 5 is a side elevation thereof.

I claim:

The ornamental design for a soldering iron head or the like, substantially as shown.

PAUL E. SPAHN.
